GRIP-LIFT ADAPTER FOR DOOR LATCHES OR THE LIKE

Robert E. Brown, 3725 Baldwin St., El Monte, Calif.
91731; and Clyde L. Vance, 10320 Pinehurst Ave.,
South Gate, Calif. 90280

Filed Apr. 10, 1972, Ser. No. 242,890

Term of patent 14 years

Int. Cl. D8—06

U.S. Cl. D8—161

Fig. 1.

Fig. 2.

Fig. 3.

Fig. 4.

Fig. 5.

FIG. 1 is a perspective view of a grip-lift adapter for door latches or the like of our new ornamental design;
FIG. 2 is a front-elevational view thereof;
FIG. 3 is an elevational view taken from the side opposite that shown in FIG. 1;
FIG. 4 is a rear-elevational view thereof; and
FIG. 5 is a top plan view of our new ornamental design thereof.

We claim:
The ornamental design for a grip-lift adapter for door latches or the like, as shown and described.
